UNITED STATES PATENT OFFICE.

HARRY HERTZBERG, OF BROOKLYN, NEW YORK.

ROTARY CONCENTRATOR, CLASSIFIER, AND SEPARATOR.

1,236,839.

Specification of Letters Patent.

Patented Aug. 14, 1917.

Application filed June 10, 1915, Serial No. 33,342. Renewed June 29, 1917. Serial No. 177,802.

To all whom it may concern:

Be it known that I, HARRY HERTZBERG, a citizen of the United States, and resident of

[5] Kings and State of New York, have invented certain new and useful Improvements in
Rotary Concentrators, Classifiers, and Separators; and I do hereby declare the following
10 to be a full, clear, and exact description
of the invention, such as will enable others
skilled in the art to which it appertains
to make and use the same.

This invention relates to concentrating, classifying and separating machines of the
15 rotary type for concentrating, classifying and separating ore, coal, mica, sand, placer
dirt, mineral or material that requires concentrating, classifying or separating by the
wet or dry method, and has for its object
20 the separation of the values or concentrated
mineral from the gangue or waste when
concentrating; to make a distinct separation
of the material to any desired classified size
when classifying; and to make a distinct
25 separation of any two materials having a
difference in specific gravity when separating;
upon a rotating inclined flat disk having
curved riffles with an irregular working
surface which has the effect of a large num-
30 ber of miner's pans as each depression on
the working surface of the riffle acts the
same as the miner's pan. In order to mount
a great number of riffles I use the unique
method of ending the inner ends of some of
35 the riffles at predetermined points around
the central hollow opening, the shorter riffles
feeding the longer ones and the riffles ending
at the central hollow opening doing the final
discharging into the hollow shaft.

40 This invention contemplates and embodies a structural feature, for the above purpose, which is simple and inexpensive in first cost and maintenance, requiring a minimum amount of power, water, or air (when working dry), utilizing a minimum amount of floor space and is light in weight.

The object of this invention is to avoid the difficulty experienced in machines that are operated by centrifugal, vibrating or oscillating means; to produce a machine that will work on material having a great range in sizes from very coarse to very fine, and having a great range in specific gravities from very heavy to the very lightest.

55 A further object of the invention is to produce a machine that can be installed in a

mill to be used as a concentrator, classifier, separator or as a combined concentrator-classifier, concentrator-separator, classifier-separator, that can be easily installed and 60 adjusted without the use of heavy foundations and expensive changes, taking an unclassified feed, concentrating, classifying or separating as desired.

And still a further object of this invention 65 is to produce a machine that will concentrate, classify and separate material wet when fed with water and dressed with water, or dry when fed dry and dressed with compressed air.

70 In carrying out my invention I employ the novel construction hereinafter fully described and claimed.

In the drawings accompanying these 75 specifications, like parts in the several views have been given the same reference numbers.

Figure 1, is a front view of the machine in operation, working wet.

Fig. 2, is a side view of the same.

Fig. 3, is an enlarged plan view of the 80 square riffles.

Fig. 4, is a sectional view of the square riffles.

Fig. 5, is a sectional view of a riffle made 85 of angle brass.

Fig. 6, is a sectional view of a riffle made of brass or any suitable material in the shape of a Z.

Fig. 7, is an enlarged plan view of flexible 90 riffles with corrugated working surfaces.

Fig. 8, is a sectional view of Fig. 7 on the line A, B.

The inclined disk 1 is secured to the hollow shaft 2, which revolves in the bearing 3, said bearing being adjustable to any angular position by the hand wheel 4, which is secured to the screw 5. The curved riffles 6 are secured to the upper surface of the disk by any suitable means and are so made that the inner working surfaces of the curves 95 of said riffles have irregular surfaces and end at the predetermined points 7, 8, and 9, around the central hollow opening 10. The bevel gear 11 is secured to the back of the disk 1 and is revolved by the small bevel gear 12, which is secured to the shaft 14, which has its bearings on the steel frame 17, and is driven by the pulley 15, which is secured to said shaft, and pulley 16, is the 105 loose pulley. The dressing pipes 18, and 19, 110 which are axially adjustable, are connected to the pipe 20, which extends up through

the central hollow shaft and is secured to the main bearing 3 by means of lock nut 21. Water or air under pressure is supplied to the dressing pipes from any suitable source 5 by means of the flexible pipe 22, while the water or air pressures are regulated by means of the valves 23 and 24 for dressing and spraying the mineral, and are indicated by the pressure indicator 25. The feed box 26, 10 is secured to the frame arm 33, by means of the upright adjustable bars 27 and 28, which causes the feed box to be placed in any desired angular position and it is secured in said position by means of the bolts 29, and 30. 15 The flexible baffle plate 31 is secured to the inside of the feed box to prevent the fine slimes from floating.

The concentrate launder 34 is substantially secured to the frame 17, at an angle and acts 20 as conveying means for the concentrates or coarse material 35 into the tank 36.

The inclined shaking discharge launder 37, has two compartments, the upper compartment 38, and the lower compartment 39, and are separated by the screen 40. The pivot support 41, is near the lower end of the launder; the pawl 42, at the upper end of the launder is actuated by the star shaped cam 43, that is revolved by the pulley 44, 25 which is driven by the belt 45, from the pulley 15. The washed material 46, that is too coarse to pass through the screen 40, is discharged into tank 47, and the material 48, which passed through the screen 40, is 30 discharged into the tank 49.

In Fig. 3, the curved center lines CD, EF, GH, represent the centers of the riffles along predetermined curved lines, 51, 52, and 53, are riffles, the ends of which extend to different points around the central hollow opening 10, and beginning at a common line, I—K, at the periphery of the flat disk, the riffles have a series of flat surfaces 55 and angles 56 along their entire working 45 surfaces and are secured to the pan by means of the nails or screws 57.

In Fig. 4, the square riffle 58 is secured to the disk that is made of wood or other suitable material 60, which is covered by 50 linoleum or sheet rubber 59 to prevent absorption. 61, is the lighter material which is superposed on the heavier material 62, as stratification takes place along the riffle when in operation.

55 In Fig. 5, the angle riffle 63 is secured to the disk, the lighter material 64, is superposed on the heavier material 65, as stratification takes place along the riffle in operation.

60 In Fig. 6, the Z riffle 66 is secured to the disk, the lighter material 67 is superposed on the heavier material 68, as stratification takes place along the riffle in operation.

65 In Fig. 7, the riffles 69, 70, 71 are made of flexible material, such as rubber, and have

a uniform cross section before being secured to the disk by the nails 72.

In driving the nails through the flexible riffles, the riffles expand in close proximity around the nails, producing a series of corrugations 73, along the flat working surface 74.

In Fig. 8, the flexible corrugated riffles 69, 70, 71 are secured to the disk by means of the nails 72, which produce the corrugated working surfaces 73. The light material 75 is superposed on the heavier material 76, as stratification takes place along the riffles in operation.

In operation the power applied to the pulley 15, causes the disk to revolve slowly in the direction of the arrow shown in Fig. 1. The material to be treated is fed from the feed box 26 upon the disk at the extreme right hand side; the material is held 85 by the riffles, and as the water is passed over it stratification takes place, the slow rotary motion of the disk carries the heavier material to the center of the disk where it is discharged into the central hollow shaft. 90 The lighter material is washed down across the riffles until it is free from the particles of material that must go to the center of the disk and is discharged upon the screen 40; the coarse material that remains on the 95 screen is shaken down into the tank 47, while the fine material that passes through the screen is discharged into the tank 49.

The action of the machine is shown in Fig. 1, in which stratification has taken 100 place and the various materials are held in their respective zones by the dressing water; as indicated by the small arrows, its action is continuous as long as the feed and water are not interrupted; the coarse dark marks 105 represent the mineral or coarse zone; the coarse light marks represent the gangue or coarse light zone, and the fine dark marks represent the fine mineral or slime zone.

When operating as a concentrator on 110 mineral the angle of the disk and the water pressure are adjusted, the sand or pulp is fed into the feed box 26, the clean concentrates are discharged into the tank 36; the clean gangue or tailings, free from mineral, 115 are discharged into the tank 47, the fine overflow is discharged into the tank 49, and is fed to the next machine to recover the fine mineral.

When operating as a classifier the angle 120 of the disk and the water pressure are adjusted, the material is fed into the feed box 26, the coarse classified product is discharged into the tank 36, the medium classified product is discharged into the tank 47, and the fine classified product is discharged into the tank 49; if two classifications are desired the screen 40 is removed, then the coarse classified product goes into tank 36 and the fine classified product goes into tank 49 and tank 130

47 remains empty. This method is used in cyanid mills operating with tube mills.

When operating as a separator, the angle of the disk and the water pressure are adjusted, the concentrated mineral is fed into the feed box 26, the mineral having the greatest specific gravity is discharged into the tank 36, the mineral having the lowest specific gravity is discharged into the tank 10 49, and middlings into tank 47.

Various combinations of concentration, classification, separation and sizing can be worked on this machine, depending upon the nature, grade, size and character of the 15 ore, sand or material to be treated efficiently.

It is not to be understood, however, that the invention is limited in this respect, to any material or form as shown and described, as it will be evident that many 20 changes may be made, in details of construction shown and described without departing from the scope of the invention.

Having thus described my invention, what I claim and desire to protect by Letters 25 Patent of the United States is:

1. In a rotary concentrator, classifier and separator an inclined disk rotating upon a central hollow shaft, a plurality of flexible riffles secured to said disk and securing 30 means causing the riffle to expand at intervals producing a corrugated working surface.

2. In a rotary concentrator, classifier and separator an inclined disk rotating upon a 35 central hollow shaft, a plurality of flexible curved riffles secured to the disk, securing means causing the riffles to expand at intervals producing corrugated working surfaces, said riffles commencing at a common line on 40 the periphery of the disk and ending at different points around the center opening.

3. In a rotary concentrator, classifier and separator an inclined disk, rotating upon a hollow shaft, a plurality of curved riffles 45 secured to the disk, securing means causing the riffles to expand at intervals producing corrugated working surfaces, said riffles commencing at a common line on the periphery of the disk, and ending at various 50 given points around the center.

4. In a rotary concentrator, classifier and separator an inclined rimless pan rotating upon a central hollow shaft, a plurality of

riffles secured to the pan, said riffles having working surfaces consisting of a series of 55 flat surfaces along its working surface, said riffles commencing at a common line on the periphery of the rimless pan and ending at various given points around the center.

5. In a rotary concentrator, classifier and separator an adjustably inclined rimless pan rotating upon a central hollow shaft, a plurality of curved riffles having corrugated working surfaces secured to said pan, means for rotating the pan, means for adjusting 60 the angle of the pan, and means for supporting the pan.

6. In a rotary concentrator, classifier and separator an inclined disk revolving on a hollow shaft, flexible riffles secured to said 70 disk, securing means causing the riffles to expand at intervals producing corrugated working surfaces; said riffles commencing at a common line on its periphery, and terminating at and around the central hollow 75 opening, provided with means for revolving the disk and means for adjusting the tilt of same.

7. In a rotary concentrator, classifier and separator an inclined disk revolving on a 80 hollow shaft, flexible riffles secured to said disk, securing means causing the riffles to expand at intervals producing corrugated working surfaces; said riffles commencing at a common line on its periphery and terminating at and around the central hollow 85 opening, provided with means for revolving the disk, means for adjusting the tilt of the disk and means for supporting the same.

8. In a rotary concentrator, classifier and separator an inclined disk revolving on a hollow shaft, flexible riffles secured to said 90 disk, securing means causing the riffles to expand at intervals producing corrugated working surfaces; said riffles commencing at 95 a common line on its periphery and terminating at and around the central hollow opening, provided with means for revolving the disk, means for adjusting the tilt of the disk, means for supporting the same and 100 means for feeding the disk.

HARRY HERTZBERG.
